(57) **CLAIM**

The ornamental design for a lint remover handle as shown and described.

DESCRIPTION

FIG. 1 is a perspective of a lint remover handle of the present design;

FIG. 2 is a front elevation of the lint remover handle;

FIG. 3 is a rear elevation of the lint remover handle;

FIG. 4 is a left side elevation of the lint remover handle;

FIG. 5 is a right side elevation of the lint remover handle;

FIG. 6 is a top plan of the lint remover handle; and,

FIG. 7 is a bottom plan of the lint remover handle.

The dashed lines in the figures illustrate portions of the lint remover handle forming no part of the claimed design.
